UNITED STATES PATENT OFFICE

BERNHARD HASENSTAB, OF BUFFALO, NEW YORK, ASSIGNOR TO MARKEL ELECTRIC PRODUCTS, INC., OF BUFFALO, NEW YORK, A CORPORATION OF NEW YORK

DESIGN FOR A WALL BRACKET FOR AN ELECTRIC LAMP

Application filed March 14, 1930. Serial No. 34,866. Term of patent 3½ years.

To all whom it may concern:

Be it known that I, BERNHARD HASENSTAB, a citizen of the United States, residing at Buffalo, in the county of Erie and State of New York, have invented a new, original, and ornamental Design for a Wall Bracket for an Electric Lamp, of which the following is a specification, reference being had to the accompanying drawing, forming part thereof.

In said drawing:

Figure 1 is a front elevation of a wall

bracket for an electric lamp, showing my new design, it being understood that the half of the figure shown in dot and dash outline is to be similarly ornamented as the half fully illustrated.

Figure 2 is a side elevation thereof.

I claim:

The ornamental design for a wall bracket for an electric lamp, substantially as shown and described.

BERNHARD HASENSTAB.
